UNITED STATES PATENT OFFICE.

WILLIAM GUY RUGGLES, OF NEW YORK, N. Y.

POWER TRANSMISSION.

Application filed March 3, 1919, Serial No. 280,237. Renewed April 28, 1923.

To all whom it may concern:

Be it known that I, WILLIAM GUY RUGGLES, a citizen of the United States, and resident of New York city, in the county of 5 New York and State of New York, have invented certain new and useful Improvements in Power Transmission, of which the following is a specification.

The invention relates in general to an improvement in power transmissions of the 10 type in which two separately controlled power mechanisms are operatively connected to a single rotatable member so as to cause the member to assume a speed which will be 15 the algebraic sum of the speeds of the two power mechanisms. The present application constitutes a continuation of and an improvement in the power mechanism disclosed in application for orientators, filed 20 September 9, 1918, Serial No. 253,216.

In the application above identified, and also in my previously filed application, Serial No. 162,589, filed February 16, 1917, there is disclosed as part of the completed 25 aviator training machine therein shown, a gimbal ring construction, the innermost ring of which is provided with a chair for supporting a person in position for universal articulation about a relatively fixed point 30 of reference. There is also disclosed a set of electric motor drives, one for each of the rings and the several motors are controlled from two control stations, one station being disposed so as to be operated by the person 35 in the machine and the other set positioned at an instructor's control station spaced from the machine. In the latter of these filed applications the electric connections are so disposed that both the instructor and the 40 student in the machine can actuate any of the motors and thus control the rotation of any of the rings at will. The previous disclosure also includes a motor control for each of the rings, which control is designed to be operatively responsive to the will of both the student in the machine and the operator at the instructor's station, as indicated by the successive or simultaneous actuation of their respective control of any of the motors.

The primary object of this arrangement 45 is to permit the instructor to cause a movement of the seat in any desired direction so as to impose on the seat the same movement as will be imposed thereon by a gust of wind 50 or other disturbing factor which habitually

imposes a change of position on an aeroplane while in flight. The student is enabled by actuating the proper control switch to counteract the disturbing influence of the action caused by the instructor and by exerting his 60 will through the proper actuation of the control, the student is enabled to correct the disturbing influence and rectify his position.

Broadly this object is attained both in the form constituting the subject-matter of this disclosure and in the form disclosed in the prior application, Serial No. 235,216 by 65 flexibly connecting two reversible electric motors to each ring and so arranging the same that the simultaneous actuation of the two motors will impose upon the ring a speed which will be the algebraic sum of the speed of the two motors. With such a connection the speeds are added when the motors are rotating in that direction which will 70 cause the ring to turn in that direction and the resulting speed of the ring is the difference between the two speeds of the motor when the motors are running in opposite 75 directions.

The primary object of the invention constituting the subject-matter of this disclosure is to provide a simple, compact, flexible type of drive between each of the electric 80 motors with their co-related motor supports 85 or mechanism containing housings, and the driving and journalling shaft common to both power mechanisms.

Still another object of the invention incidental to the desideratum for simplicity 90 of construction is to provide, in a device of the class described, an organization of parts which can be secured and maintained positively in preset driving position, and which can be readily dismounted for repair or substitution of parts.

Various other objects and advantages of the invention will be in part obvious from an inspection of the accompanying drawings and in part will be more fully set forth in 100 the following particular description of one form of mechanism embodying my invention, and the invention also consists in certain new and novel features of construction and combination of parts hereinafter set 105 forth and claimed.

Referring to the accompanying drawings:

Figure 1 is a view partly in side elevation 110 of one of the power mechanisms fixed to one

of the sets of rings disclosed in the preceding applications and partly in section taken on the line 1—1 of Figure 2;

Figure 2 is a view partly in end elevation 5 and partly in section axially of the supporting shaft of the two mechanisms and taken on the line 2—2 of Figure 1; and

Figure 3 is a transverse sectional view 10 taken on the line 3—3 of Figure 2.

10 In the following description and in the claims, parts will be identified by specific names for convenience of expression but they are intended to be as generic in their application to similar parts as the art will 15 permit.

In the accompanying drawings there is 20 shown two sets of supports 10 and 11 which are any two pairs of the gimbal ring disclosed in the two prior applications. As 25 the construction is obviously adapted for use in other locations than in connection with the gimbal ring construction featured in the prior application, the rings will be identified in this application indifferently 30 as supporting or supported members.

In the present disclosure and for the purpose of simplifying the description, it will 35 be considered that the ring 10 acts to constitute a single supporting member and that 40 the ring 11 similarly acts to constitute a single supporting member mounted for rotary movement relative to the supporting member about the axis of a centrally disposed shaft 12 loosely mounted in both 45 members.

The supported member 11 is controlled 50 by a pair of reversible electric motors 13 and 14 operatively connected to the supported member through the mechanism, 55 hereinafter described, so as to turn the member in either direction and over any desired angle of movement up to 360°, or beyond, as desired. The motors are mounted, respectively, in housings 15 and 16 positioned at opposite ends of the shaft 12. It is understood that the detail description of one of the housings and its contained parts, as shown in section to the right of Figure 2, is the same as that shown to the left of this figure, except for the obvious reversing positions. The right side of the mechanism is illustrated in detail but it will be understood that in the following description the parts referred to at the right of the shaft 60 are duplicated and symmetrically disposed to the left of the shaft.

The housings 15 (or 16) is rotatably mounted on the shaft 12 by means of two spaced apart anti-friction roller bearings 17 and 18; the anti-friction bearing 17 being positioned in line with the supported member 11 and the anti-friction bearing 18 constituting an out-bearing for the adjacent end of the shaft. The end out-bearing is 65 positioned in the hub of a wheel shape bear-

ing plate 19 fastened to the outer end of the casing 16. The end of the casing carrying the roller bearing 17 is enlarged to provide an extensive engagement with the member 11 (or 10) and is provided with an inwardly extending and massive wall 20 having its outer side recessed to provide a pocket 21 for receiving the bearings. The bearings are held in place by an end plate 22 encircling the shaft and bolted to the wall 20. 70 This end of the casing is shaped on opposite sides of the shaft to provide seats 23 for the ring shaped members 11 (or 10) which are held in place by a face plate 24 fastened by bolts 25.

A planetary gear train is mounted within the housing adjacent the wall 20. This train includes an intermediate gear carrying spider 25 splined to the shaft 12 and bearing upon the anti-friction bearings 17 to hold the same in set position against the plate 22. A packing ring 26 surrounds the reduced hub 27 of the spider and is in turn held in place by a metal bearing ring 28. The packing and bearing rings constituting 80 a means at one end of the casing for preventing the leakage of lubrication from the mechanism containing portion 29 of the casing along the shaft 12. An end plate 29' 85 closes the outer end of the casing and encloses the mechanism in a bath of lubrication. Removal of this end plate permits access to the mechanism without the necessity for demounting any of the said mechanism.

The planetary gear train includes an end gear 30 in the form of an internal gear fixed to the inner side of the housing so as to turn therewith. A relatively long center gear pinion 31 constitutes the other end member of the gear train and is loosely mounted on the shaft 12. The portion of the shaft between the part carrying the pinion and the spline portion is threaded and provided with a nut 32 which bears against a shoulder 33 defining the inner end of the spider hub. In this way the spider is fixed in position longitudinally of the shaft, thus insuring the maintaining of the intermediate gears 34 in their set meshing engagement as hereinafter described. Further this nut locking arrangement not only places the gasket 26 under preset pressure but also acts to secure the bearings 17 in their initially set position. Considering it 105 in another aspect, the nut 32 prevents the shaft from moving to the left and correspondingly the similar nut in the housing 15 prevents the shaft from moving in the opposite direction. The floating spider is provided with three circumferentially spaced apart and longitudinally extending stub shafts 35, upon each of which is mounted one of the intermediate gears 34 as shown in outlines in Figure 3. Each of these gears 110 constitutes an intermediate gear of the train 120

and meshes respectively with the center pinion 31 and with the internal gear 30. By this construction it is apparent that with the spider stationary or relatively stationary the rotation of the pinion will rotate the gear 30, through the gears 34, and with the pinion stationary the revolving of the spider will likewise rotate the gear 30. The motor 14, as shown in Figure 1, is mounted on an extension 37 from the housing 16 so as to permit the ready dismounting of the same for repairs and substitution of parts.

A worm shaft 38 has one end mounted in an end thrust bearing 39 held in place by an end cap 40. The opposite end of the shaft is slotted, as shown at 41, and is keyed to the outer end of the armature shaft 42, so as to permit the ready withdrawal of the worm shaft independent of the armature shaft when the end thrust bearing is demounted from the casing. The worm shaft is provided centrally thereof with a high pitch worm 43 in mesh with the periphery of a gear wheel 44 loosely mounted upon a reduced end portion 45 of the shaft. This mounting is provided by means of roller bearings 46 held in set position on the shaft against a shoulder 47 defining the inner end of the reduced portion 45. An end nut 48 which is threaded to the end of the shaft bears against the out-bearing 18 and there-through against an intermediate filler ring 49 and the bearing 46 to insure the maintenance of the preset driving connection between the worm 43 and the gear wheel 44.

The gear wheel 44 constitutes one element of a friction clutch of the plate type. The clutch includes a series of relatively large plates 50 mounted to face a flat side of the gear 44 and held in position, against rotary movement relative to the gear 44, by means of a series of pins 51 and 52. The pins 52 are headed and are each controlled by a spring 53 acting through the head to hold the plates in frictional engagement with their cooperating and relatively small diameter clutch plates 54. The clutch plates 54 are positioned between the plates 50, and except for the frictional resistance usual in such constructions, are free under high torsional action of the parts to move relative to the plates 50. The plates 54 are each provided with a central opening serrated and meshing with the central gear pinion 31 in offset relation to the portion of the pinion in mesh with the three intermediate gears 34.

It is understood that normally there is no slippage between the two sets of plates constituting the clutch and there is formed, in effect, a rigid driving connection between the gear 44 and the pinion 31. The clutch is introduced simply as a safety device in case the motor is attempting to turn the casing and its supported member against

an abnormal resistance to its rotary movement.

In operation, and assuming first that the shaft 12 is locked against rotary movement with reference to the supporting member 10 and assuming that the circuit is closed through the motor 14 to actuate the same and thus turn the worm gear 43 in one or the other of its rotary directions the shaft 12 is caused to turn. Such a movement of the armature shaft will act through the gear 44 and its attached clutch to evolve the central gear pinion 31 about the shaft. The turning of the pinion will act through the intermediate gears to rotate the same as their supporting shafts are held in place, due to the fact that the shaft 12 is held against rotation. Motion is thus transmitted to the internal gear 30, revolving the same and thus turning the housing 16 and its supported member 11 bodily about the axis of the shaft 12. Therefore, by causing the motor 14 to function, the supported member 11 will be caused to revolve at a speed dependent upon the speed of the motor and upon the ratio of speed reduction by the gear train. In thus revolving, the supported member 11 will, of course, carry with it the housing 16 and the motor 14 and will revolve the same bodily about the axis of the shaft 12.

Again let it be assumed that the motor 14 is inactive and that through the actuation of the motor 13 the shaft 12 is caused to revolve. This will obviously take place for the motor 13 is fixed in space due to the assumption that the supporting member 10 is fixed in place. As the motor 13 cannot turn the housing 15 it reacts on the shaft to turn the same. Considering the casing 16 it will be noted that as the high pitch of the worm 43 prevents the gear 44 from turning the worm wheel, the gear 44 will thus be locked in position against rotation about the shaft. Thus the clutch and the pinion 31 will be locked against rotary movement about the shaft 12. The turning of the shaft, however, acts through the spider to revolve the same about the fixed central pinion 31 and acts through the intermediate gears to revolve the same and thus rotate gear 30, the casing 16 and its supported member 11. In this way it is seen that each motor can contribute to the rotation of the housing 16 and its attached supported member 11. In other words, either motor can rotate the supported member in either of its rotary directions. Not only will this action take place when only one of the motors is active but it will likewise take place when both of the motors are active. If the armature shafts of both of the motors are rotating in a direction to cause the supported member to move in the same direction then the speed of rota-

tion of the supported member will be the sum of the speeds of the two motors. If, however, the motors are turning in a direction so that one of them is tending to turn the supported member in one direction and the other is tending to move the supported member in the reverse direction, then the resulting speed of the supported member will be the difference in speed between the speed of the two motors. In other words, the supported members will have a speed equal to the algebraic sum of the speeds of the two motors.

It is possible by means of a device of this character to provide two sets of controls, ring or other member, each operatively connected to govern one of the motors and so arranged that a person at one of the control stations can move the supported member into any desired angular position and the person at the other control station can reset the supported member into the previous or into any other desired position. Further, it is possible for both operators to each individually impose his will upon the resulting position of movement of the supported member.

While I have shown and described, and have pointed out in the annexed claims, certain novel features of my invention, it will be understood that various omissions, substitutions and changes in the form and details of the device illustrated and in its operation may be made by those skilled in the art without departing from the spirit of the invention.

Having thus described my invention, I claim:

1. In a device of the class described, the combination of a support, a shaft rotatably mounted in said support, a power mechanism carried by said support and operatively connected to said shaft to rotate the same, a member mounted for rotary movement relative to said support, a second power mechanism carried by said rotary member and provided with a high pitch driven worm and a gear meshing with said worm and operatively connected to said shaft to rotate the member relative to said rotatable shaft.

2. In a device of the class described, the combination of a support, a shaft rotatably mounted in said support, a power mechanism carried by said support, a driving connection between the power mechanism and said shaft to rotate the same, a member mounted for rotary movement relative to said support, a second power mechanism carried by said rotary member, a second driving connection between said second power mechanism and said shaft, said connection including power transmission means operable by the power mechanism and interposing a resistance to rotation thereof by

the shaft, both of said driving connections including slip clutches for permitting movement of the shaft independent of both of said power mechanisms.

3. In a device of the class described, the combination with a shaft of a support rotatably mounted on said shaft, a member mounted for rotary movement relative to said support, and about said shaft, a pair of power mechanisms, one carried by the support and the other by the member and a driving connection between each of said power mechanisms and said shaft, whereby the member is free to have a movement which will be the algebraic sum of the movements imposed thereon by the several power mechanisms, said connections each including means for transmitting power therethrough in one direction and resisting the transmission in the other direction.

4. In a device of the class described, the combination of a support a shaft carried by the support, a member mounted on said shaft for rotary movement relative to said support, a rotary power mechanism carried by said member to rotate the same, a planetary gear train carried by the shaft and constituting a driving connection between said power mechanism and said member, and a second reversible power mechanism carried by the support and operatively connected to one of the gears of said train to assist or retard the movement of said member.

5. In a device of the class described, a supported member mounted for rotary movement about an axis, and power means for rotating the member, said means including a supporting member, a main shaft disposed concentric with said axis and loosely journaled in said supporting member, a gear loose on said shaft, a power shaft carried by said supporting member, a driving slip clutch between said power shaft and said gear, a planetary gear connection between said gear and said shaft, said supported member mounted loose on said shaft and a gear connection between said shaft and said supported member whereby the supported member may be rotated from said power shaft.

6. In a device of the class described, the combination of a shaft, a member supported by and mounted for rotary movement about said shaft, two reversible power mechanisms, one revolvably mounted on the rotary member and each operatively connected to said member to rotate the same in either direction, a flexible driving connection between each of said mechanisms and said shaft for causing the speed of one of the mechanisms to be added to and subtracted from the speed of the other mechanisms whereby the resulting speed of the member will be the algebraic sum of the speeds of the two mechanisms and anti-friction bear-

ings between the flexible driving connections and said shaft.

7. In a device of the class described, the combination of a support, a shaft mounted 5 for rotary movement in said support, a pair of reversible power mechanisms, one carried by said support and the other rotatably mounted on said shaft fixed relative thereto and each mechanism being operatively connected to said shaft to rotate the same in either direction.

8. In a device of the class described, the combination of a main shaft, two power mechanisms for independently and collectively driving said shaft in either direction, gear connections between each mechanism and the shaft, one of said power mechanisms mounted on the shaft and rotatable relative thereto, said mechanisms each including a 20 worm drive of high pitch whereby the mechanisms can drive the shaft but the shaft cannot drive the mechanisms.

9. In a device of the class described, the combination of a main shaft, two power mechanisms for independently and collectively driving said shaft in either direction, gear connections between each mechanism and the shaft, said mechanisms each including a worm drive of high pitch whereby the 30 mechanisms can drive the shaft but the shaft cannot drive the mechanisms and each gear connection including a gear of relatively large diameter meshing with said worm drive and a slip clutch drive including plates 35 fixed to said large gear, said slip clutch drive normally constituting a rigid driving connection and permitting slippage only under abnormal torque conditions.

10. In a device of the class described, a 40 main shaft, an anti-friction device mounted on said shaft, a mechanism containing housing mounted on said anti-friction device, a planetary gear set including a spider splined to said shaft and engaging said anti-friction 45 device to hold the same in place, locking means for securing the spider in place, a power shaft carried by the housing and operatively connected to said planetary gear set.

50 11. In a device of the class described, a main shaft, an anti-friction device mounted on said shaft, a mechanism containing housing mounted on said anti-friction device, a planetary gear set including a spider splined to said shaft and engaging said anti-friction 55 device to hold the same in place, a power shaft carried by the housing and operatively connected to said planetary gear set and an out-bearing for the end of the main shaft 60 carried by the housing and tending to maintain the driving connection between the power shaft and the main shaft fixed in position.

65 12. In a device of the class described, the combination of a main shaft, a mechanism

containing housing loose on said shaft and free to turn about the same at all times, a gear train for effecting relative movement between the housing and shaft and including an internal gear defining one end of the train 70 and fixed to said housing, a center gear pinion defining the other end of the train and loose on said shaft, an intermediate gear having its axis of rotation fixed to and revoluble with the shaft, a power shaft journaled in the housing and a driving gear connection within the housing for driving the center gear pinion from the power shaft to rotate the same.

75 13. In a device of the class described, the combination of a main shaft, a mechanism containing housing loose on said shaft, a gear train including an internal gear defining one end of the train and fixed to said housing, a center gear pinion defining the 80 other end of the train and loose on said shaft, a power shaft journaled in the housing, a two-part clutch with one of the parts supported loose on the main shaft and in driving connection with the power shaft and the other part in driving connection with the pinion.

85 14. In a device of the class described, a mechanism containing housing, a main shaft journaled therein at two spaced apart points, driving mechanism carried by said shaft between said points, said mechanism including a planetary gear train connected to the shaft with one element thereof loosely mounted on the shaft and another element in driving engagement with the housing, a clutch element carried by the shaft and operatively connected to the gear train, a power means for driving said clutch element.

90 15. In a device of the class described, the combination of a main shaft having a reduced outer end forming a shoulder, a housing enclosing the end of the main shaft, a power shaft mounted for rotary movement in said housing, an end bearing for supporting the shaft in the housing for securing the axis of the power shaft in set 100 relation to the axis of the main shaft, a clutch element including a worm gear connection with the power shaft, an anti-friction bearing for the clutch element, said bearing mounted on the shaft between the shoulder and the end bearing and means for securing the clutch, anti-friction bearing and the shaft end bearings in set position filling said reduced outer end of the main shaft and driving means connecting the clutch element with the main shaft.

115 16. In a device of the class described, the combination with a main shaft and a housing mounted for relative rotary movement about the axis of the shaft, of a power shaft mounted for rotary movement in said housing and extending into the same at right 120 125 130

angles to the axis of the main shaft, a gear train driving connection between said shafts with one of the gears fixed to the housing and another of the gears fixed to the shaft and bearings spaced apart in said casing and engaging the shaft for securing the axes of said shafts securely in relatively fixed position.

17. In a device of the class described, 10 the combination with a main shaft and a power shaft support mounted for relative rotary movement about the axis of the main shaft, of a power shaft journaled in said support, a planetary gear train with the 15 last element thereof fixed to the support and the first element thereof loose on the shaft and operatively connected to the power shaft to be driven thereby and intermediate elements thereof carried by the main shaft 20 with their axis of rotation fixed relative to the shaft, said intermediate element constantly meshing with both the first and last elements of the gear train.

18. In a device of the class described, 25 the combination with a main shaft and a power shaft support mounted for relative rotary movement about the axis of the main shaft, of a power shaft journaled in said support, a planetary gear train with the 30 last element thereof fixed to the support, a driving clutch having one member geared to the power shaft and the other element geared to the first element of the gear train, and intermediate elements thereof carried 35 by the main shaft and meshing with both the first and last elements of the gear train.

19. In a device of the class described, 40 the combination of a main shaft provided in order with a housing anti-friction bearing, a planetary gear spider splined thereon, a nut for securing the spider in place, a loosely mounted pinion, a clutch anti-friction bearing, a second housing anti-friction bearing and a nut for securing said 45 second anti-friction bearing in place, a housing carried by said two housing anti-friction bearings, an internal gear carried by said housing, an intermediate gear meshing with said internal gear and with said pinion to form a gear train, a clutch mounted 50 on said clutch anti-friction bearing and engaging said pinion and power means for driving said clutch.

20. In a device of the class described, 55 the combination of a main shaft provided in order with a housing anti-friction bearing, a planetary gear spider splined thereon, a nut for securing the spider in place, a loosely mounted pinion, a clutch anti-friction bearing, a second housing anti-friction bearing and a nut for securing said second 60 anti-friction bearing in place, a housing carried by said two housing anti-friction bearings, an internal gear carried by said 65 housing, an intermediate gear meshing with

said internal gear and with said pinion to form a gear train, a clutch mounted on said clutch anti-friction bearing and engaging said power pinion, power means carried by said housing and a worm drive connection 70 between said power means and said clutch whereby the power means can drive the clutch through said worm drive and said worm drive acting to prevent the clutch from rotating the power means and thus 75 act to lock the driving connection between the clutch and power means.

21. In a device of the class described, the combination of a lubrication containing 80 housing, a head for closing an end thereof, a main shaft mounted for rotary movement in said housing and having one end extending into said housing and terminating therein adjacent said head, an end bearing for said end of the shaft, a gasket between the 85 shaft and the housing at the end thereof receiving the shaft, driving mechanism contained in said housing between the end bearing and said gasket, said mechanism including a power shaft, a gear train having its 90 first element operatively connected to be driven by the power shaft, its last element fixed to said housing to revolve the same and an intermediate element carried by said shaft.

22. In a device of the class described, the combination of a lubrication containing 95 housing, a head for closing an end thereof, a main shaft mounted for rotary movement in said housing and having one end extending 100 into said housing and terminating therein adjacent said head, an end bearing for said end of the shaft, a gasket between the shaft and the housing at the end thereof receiving the shaft, driving mechanism contained in said housing between the end bearing and said gasket, said mechanism including a power shaft, a slip clutch having one 105 element thereof geared to said power shaft, a gear train having its first element geared to the other element of the slip clutch, the last element of the gear train fixed to said housing to revolve the same and an intermediate element of said gear train carried by 110 said shaft.

23. In a device of the class described, the combination of two supports, a motor mounted on each support, a main shaft loosely mounted in both supports, a planetary gear train for each motor, each of said gear trains including an end gear fixed to its corelated support to turn the same relative to the shaft, the other end gear operatively connected to its corelated motor to be driven thereby and a spider fixed to the 120 shaft to revolve therewith and having an intermediate gear journaled in said spider and meshing with the first and last gears of the gear train.

24. In a device of the class described, the 130

combination of two supports, a main shaft loosely mounted in both supports, an electric motor mounted on each support, a driving connection between each motor, its support and the shaft, each of said driving connections including a reducing gear train having a worm gear engagement with the armature shaft of its correlated motor where- by the motor can drive through the connection but the connection is locked against 10 moving the armature shaft.

Signed at New York city, in the county of New York and State of New York, this 28th day of February, A. D. 1919.

WILLIAM GUY RUGGLES.
